RECEPTACLE-FEEDING MECHANISM.

1,330,596.

Specification of Letters Patent. Patented Feb. 10, 1920.

Application filed August 14, 1917, Serial No. 186,182. Renewed October 7, 1919. Serial No. 329,145.

To all whom it may concern:

Be it known that we, EDGAR R. LOWEREE, GEORGE F. JACKSON, and RALPH A. GLEASON, citizens of the United States, and residents of Baltimore, Maryland, have invented certain new and useful Improvements in Receptacle - Feeding Mechanism, of which the following is a specification.

This application in part comprises subject matter like that contained in an application filed by us January 19, 1917, #143,364.

Our invention concerns the feeding of receptacles, such as can bodies or the like to machines, which are to act thereupon, and one object of the invention is to provide a feeding means which will engage the can bodies one after the other, and will move them with an accelerating speed from the station where the engagement of the feeding means therewith takes place to a point of discharge, the can bodies being properly re-spaced at the point of discharge, so that they may be acted upon by the machine in proper time.

The invention consists in the features and combination and arrangement of parts hereinafter described and particularly pointed out in the claims.

In the accompanying drawings;

Fig. 1 is a plan view of the feeding mechanism and this view also includes a portion of the machine to which the can bodies are fed.

Fig. 2 is a vertical sectional view of Fig. 1.

Fig. 3 is a plan view of a modification, and,

Fig. 4 is a vertical sectional view of said modification.

The apparatus includes a series of traveling arms 1, for engaging the can bodies at a station A and delivering them at another station, for instance, at the point B and in this action the can body is accelerated in its speed of movement from station A to station B and respaced in relation to the other can bodies of the series being fed. The arms 1 are adapted to swing about vertical pivots 2, which connect the said arms with the rotating head or disk 3, the pivots consisting of rods 4, suitably journaled in the upper flange 5, and the lower bearing 6 of this head or disk and said arms carrying at their outer ends fingers 7, which are pivotally mounted

at the upper outer extremities of the arms 1, as shown at 8, these fingers being in the form of weights depending from the pivots and having upwardly curved lower edges, as at 9. The disk or head 3 is in constant rotation and it receives upon its upper surface the can bodies which are, therefore, supported on the rotary disk and they are propelled with the said disk by means of the fingers 9 engaging the can bodies and pushing them in the direction of the arrow *a* shown in Fig. 1. The can bodies may be delivered onto the head or disk 3 in any suitable way but we prefer to employ an initial disk or feeding member 10, which receives the cans direct from a suitable exhaust box or conveyor. Guides 11 and 12, associated with the initial feed disk 10, serve to direct the cans, as indicated by the arrow *b* and as the initial disk 10 overlaps the head or disk 3 the can bodies moving in the direction of the arrow and directed by the guides will be delivered between the arms or fingers 9 to be propelled onward thereby.

The initial feeding disk 10 is rotated at a sufficiently high rate of speed in relation to the rotation of the spacing disk or head 3 to crowd or tend to crowd the can bodies onto said spacing disk to be taken by the propelling fingers but should a propelling finger be in such a position that a can body will strike or press upon the outer edge or end of the finger 9, this finger, being as stated in the form of a pivoted member, will yield and pass by this particular can body and the next oncoming finger will take this particular can body and propel it onward, said can body in this movement being under the control of the guide 12 and resting upon the rotating spacing disk 3.

As above indicated the movement of the can body is accelerated or gradually increased from station A to station B in the direction of the arrow *a*, so that in the case of filled can bodies the movement imparted thereto by its propelling finger will be slow at first in order to avoid spilling the contents which would result from a sudden impulse being imparted to the can body and this slow movement will be followed by a gradually increasing speed of movement, until the can body is discharged at the station B, a guide 12' coöperating with the propelling

arms in effecting this discharge. The can bodies therefore will be taken from a condition practically at rest at the station approximately at A where they may be crowded in close order and they will be respaced or separated gradually until the proper separation or respacing has been accomplished at the station approximately at B. The increased movement of the arms 1 and their propelling fingers 9 may be accomplished in different ways but in the particular and preferred construction illustrated we employ a spider C, having slotted arms 13, extending radially from the center of the spider and receiving lugs 14 depending from the arms 1 and preferably these lugs extend down through slots 15 in the disk or head 3. The spider is mounted to turn about a post 16 held in a boss 17 of a bracket 18 forming part of the fixed frame. The spacing disk or head 3 is mounted to turn about a pin or post 16', extending up from the bracket arm 16" forming a lateral extension of the post 16, and from this construction it will be seen that the spacing disk or head 3 and the spider are eccentrically arranged in relation to each other, their pivot or journal posts 16' and 16 being displaced in relation to each other out of axial alinement. The spider 13 is rotated by a worm wheel 19 from a worm 20 on a shaft 21, which is suitably journaled in the frame-work and is driven through any suitable means, such as the bevel gearing at 22. This same shaft 21 or an extension thereof drives the initial feed disk 10 by a worm gear, indicated at 23.

It will be observed that the eccentric relation of the spider and the head carrying the propelling arms is such that at the receiving station approximating the position A the stud 14 of the propelling arm will engage the slot of the arm of the spider at a point close to the center of the rotation of the spider, as indicated on the right of Figs. 1 and 2, whereas at the discharge point approximating the position B the stud of the arm which has reached this discharge station will be engaged by the spider arm at the outer end thereof and of course at different angular positions of the rotating head between the stations A and B, the studs 14 will be in engagement with the spider arms at points progressing from the inner to the outer ends of the slots.

Obviously when the studs 14 are engaging the spider arms near their center of rotation the movement of these arms with their propelling fingers 9 will be slow, whereas when the arm reaches the discharge station approximating the position B and the stud 14 is engaged by the outer end of the spider arm the speed of the arm will be at its greatest and as the arm travels from station A to station B and its stud progresses outwardly along the slot of the spi-

der arm the speed of the arm will be progressively increased, thus effecting the respacing or gradually increasing separation of the can bodies and increasing the speed of movement of said can bodies, so that at the point of discharge they will be respaced at proper distances apart to suit the movement or periods of movement of the parts of the machine which are to act thereon and if the can bodies are to be propelled by a part of the main machine the speed of the can body when discharged from the respacing head and delivered to this moving part of the machine will accord with the speed of said part, so that there will be no sudden acceleration of speed and no sudden impulse imparted to the can body which would tend to spill the contents.

As an instance of means which may be associated with the feeding mechanism to receive the can bodies therefrom we show a continuously rotating ring 24 having dogs 25 projecting above the plate or frame 26, said frame being slotted at 27 to receive this dog ring. The can bodies are delivered onto the main frame 26 of the main machine in front of the traveling dogs 25, which engage the can bodies and propel them onward between the guides 12 and 12' to stations at which suitable mechanism acts upon the can bodies.

The head 3 will be kept in rotation because of the movement imparted thereto from the spider C by way of the arms 1, this transmission of power being continuously exercised.

We do not limit ourselves to the construction shown and as an illustration of the variations that might be employed within the scope of our invention reference is made to Figs. 3 and 4. In these figures the propelling arms 1^a are arranged to yield like the arms or fingers 9 when a can body is not properly engaged thereby, but presses upon the end of the arm. For this purpose the arms are slotted at 28 to receive their pivot pins 4^a. The head 3^a carrying this pivot point is arranged eccentrically in relation to the spider 13^a and instead of employing slotted arms, this spider carries supplemental arms 29 pivotally mounted at 30 to the spider arms and these supplemental arms 29 are pivotally connected to the propelling arms 1^a at points 31 intermediate of the length of said propelling arms. The supplemental arms have tail portions 29' connected by springs 32 to the preceding supplemental arm 29 at the point 33 intermediate of the length thereof, and from this construction it will be seen that as the spider rotates it will pull around with it the propelling arms 1^a through the medium of the supplemental arms 29.

It will be observed that if a propelling arm strikes the can body end on or partly

end on instead of engaging the can body with its lateral face the said propelling arm can yield radially inward in respect to the head or disk 3^a, this being permitted by the 5 spring 32, which holds the supplemental arm 29 yieldingly and also this action is permitted by the slotted construction at 28. The mounting of the rotary head and the spider is different in this modification from 10 that first described, involving a member 34 mounted in the bracket 18', said member having a bearing at 35 for the worm wheel 36, which carries the hub 37 of the spider and the rotary spacing head being carried 15 by a center pin 38 mounted in the member 34. The rotary spacing head is slotted at 39 to permit connection to be made between the supplemental arms 29 and the propelling arms 1^a.

20 Features relating to the ring 24 having dogs 25, and the slotted table are made the subject of another application.

What we claim is:

1. In combination with mechanism acting 25 in conjunction with can bodies, means for feeding said can bodies comprising arms for respacing the can bodies as delivered thereto and for transporting them, a moving support for said arms, and means for moving 30 said arms continuously in one direction, and in succession giving them individually a progressively accelerated movement in respect to and in the same direction with said support, from the point at which the arms 35 take the can to the point of discharge from the arms, said arms from the latter point to the point of first engagement with the bodies having their speed of movement reduced, substantially as described.

40 2. In combination with mechanism acting in conjunction with can bodies, means for feeding said can bodies comprising a series of substantially radially disposed fingers, a rotary carrier for said fingers and means for 45 giving said fingers a progressive increase of speed in the same direction with and in respect to said rotary carrier to more widely separate the bodies after they have engaged therewith and until the bodies are 50 charged from the arms for properly spacing said moving bodies, substantially as described.

3. In combination with mechanism acting 55 in conjunction with can bodies, means for feeding can bodies comprising a rotary table onto which the can bodies are delivered, and radially disposed fingers for engaging the can bodies with means for revolving said table and fingers about a common center 60 and for accelerating the movement of the fingers progressively after engaging the bodies in the same direction with and in relation to the said rotary table and until the can bodies are delivered by said arms to re- 65 space the same progressively until they are

separated at proper distances apart to be delivered from the rotary table, substantially as described.

4. In combination with mechanism acting 70 in conjunction with can bodies, means for feeding can bodies comprising a series of rotary fingers, a rotary carrier therefor on which the fingers are pivotally mounted, said fingers as a series rotating with said carrier about a common center, and means 75 for giving the fingers individually and successively a progressively accelerated movement in the same direction with and in respect to the rotary carrier after they engage the can bodies and until they deliver the said 80 can bodies for respacing the bodies for their delivery, substantially as described.

5. In combination with mechanism acting 85 in conjunction with can bodies, a carrier, a plurality of radially disposed fingers rotating with said carrier as a group, means for accelerating the movement of said arms individually in the same direction with and in respect to the carrier for spacing the can bodies, said fingers being yieldable radially 90 under pressure from the can bodies to prevent damage to the can bodies, substantially as described.

6. In combination with mechanism acting 95 in conjunction with can bodies, a carrier, a plurality of radially disposed fingers rotating with said carrier as a group, means for accelerating the movement of said arms individually in the same direction with and in respect to the carrier for spacing the can 100 bodies, said fingers being yieldable radially under pressure from the can bodies to prevent damage to the can bodies, said carrier serving as transporting means for can bodies.

7. In combination with mechanism acting 105 in conjunction with can bodies, a carrier, a plurality of radially disposed fingers rotating with said carrier as a group, means for accelerating the movement of said arms individually in the same direction with and in respect to the carrier for spacing the can bodies, said fingers being yieldable radially 110 under the pressure from the can bodies to prevent damage to the can bodies, said carrier serving as transporting means for can 115 bodies, and guide means over the rotary carrier forming a guideway for the bodies.

8. In combination with mechanism acting 120 in conjunction with can bodies, and feeding means for the can bodies comprising two rotary members arranged one above the other but with their axes eccentrically disposed in relation to each other, one of said carriers having a series of radially disposed fingers pivotally mounted thereon at their 125 inner ends, and the other carrier having connection with the fingers at points intermediate their pivots and their outer ends, whereby through a certain degree of angular movement the speed of the fingers will 130

- be accelerated to progressively separate the successive can bodies relative to each other as they are transported to the point of delivery, substantially as described.
5. 9. In combination with mechanism acting in conjunction with can bodies, a carrier, a plurality of propelling fingers thereon to engage the can bodies while close together, means for giving the fingers in succession a 10 progressively accelerated movement in relation to and in the same direction with the carrier to separate the can bodies progressively greater distances apart as they move onward, said fingers being yieldingly 15 mounted to move thereby preventing damage to the can bodies when contacting end on therewith, substantially as described.
10. In combination with mechanism acting in conjunction with can bodies, and 20 feeding means for the can bodies comprising two rotary members arranged one above the other but with their axes eccentrically disposed in relation to each other, one of said members having a series of radially disposed 25 fingers pivotally mounted thereon at their inner ends, and the other member having connection with the fingers at points intermediate their pivots and their outer ends, whereby through a certain degree of angular movement the speed of the fingers will 30 be accelerated to progressively separate the successive can bodies relative to each other as they are transported to the point of delivery, said fingers having their outer ends 35 yielding mounted, substantially as described.
11. In combination in receptacle feeding mechanism, a moving carrier, a series of arms mounted thereon to be carried thereby, said arms being pivotally mounted on said 40 carrier to swing in a horizontal plane, means for giving the arms an accelerated movement in respect to and in the same direction as that of the moving carrier and fingers pivotally mounted on the arms to have yielding movement automatically upon striking a receptacle body, substantially as described.
12. In combination in receptacle feeding mechanism, carrier means rotating about a vertical axis, arms mounted on said carrier 50 means, fingers pivotally mounted at the outer ends of the said arms to move the receptacle bodies along and to yield upon striking a receptacle body, and means for operating the carrier, said fingers turning 55 about horizontal pivots, substantially as described.
13. In combination a carrier, means for rotating the carrier, fingers arranged radially in respect to the center of rotation to 60 take and move receptacles and pivoted to swing in vertical planes to yield upon being struck by the receptacles to be moved by said fingers, and means for presenting the receptacles in position to be taken by said 65 fingers, substantially as described.
14. In combination a rotary carrier, arms pivotally mounted thereon to swing in relation to said carrier in a horizontal plane, means for giving said arms an accelerated movement progressively as they are moved 70 by the carrier, fingers pivotally mounted on said arms to swing in vertical planes, said arms and fingers being arranged substantially radially relative to the carrier, substantially as described. 75
15. In combination a carrier, arms pivotally mounted on said carrier and extending substantially radially relative thereto, means for operating the arms to give them an accelerated movement in the same direction with and in respect to the carrier, said carrier being moved by the movement of said arms mounted thereon, substantially as described. 80
16. In combination a carrier rotating 85 about an axis, receptacle propelling arms pivotally mounted on the carrier to swing in a horizontal plane, a member rotating below the carrier on an axis eccentrically disposed in relation to the axis of the carrier, said member having connection with the horizontally movable arms to impart motion thereto and thereby impart motion to the carrier of said arms, substantially as described. 90
17. In combination a carrier, arms mounted thereon to swing in a horizontal plane, weighted fingers at the outer ends of said arms turning about horizontal pivots thereon and extending substantially radially in respect to the carrier, means for rotating the 95 carrier and arms and for giving the arms an accelerated movement in respect to and in the same direction with the carrier, substantially as described. 100
18. In combination a rotary carrier, arms pivoted on the carrier to turn in a horizontal plane relative to said carrier, a member arranged eccentric to the axis of the carrier and having guides receiving projections from the pivoted arms for propelling said 105 arms, substantially as described. 110
19. In combination a rotary carrier, arms pivoted on the carrier to turn in a horizontal plane relative to said carrier, a member arranged eccentric to the axis of the carrier 115 and having guides receiving projections from the pivoted arms for propelling said arms, and yielding fingers at the outer ends of said arms, substantially as described.
20. In combination a rotary carrier, arms pivoted thereto to swing in a horizontal plane, said carrier being slotted and said arms having pins depending through said slots, a member below the carrier turnable on an axis eccentric to that of the carrier 125 and having radial guides to receive the depending pins, whereby the arms are propelled, substantially as described. 120
21. In combination a carrier, arms pivotally mounted thereon to swing in a hori- 130

- zontal plane relatively thereto, a member below the carrier turnable on an axis eccentrically disposed relative to the axis of the carrier, a slip joint connection between said member and the arms to drive said arms with an accelerated movement from one point to another, a post on which said member turns, a post on which the carrier turns and a bracket connecting the disaligned posts, substantially as described.
22. In a can body feeder, a plurality of fingers to engage the can bodies by the lateral sides of said fingers, a movable carrier for said fingers, said fingers being yieldingly mounted to yield on striking a can body end on, and means for giving the fingers an accelerated movement in the same direction with and in respect to the movement of the carrier, substantially as described.
23. In a can body feeder, a plurality of arms, a carrier to which the arms are pivotally connected, means for giving the arms
- an accelerated movement and fingers yieldingly mounted on the arms to yield on striking a can body end on, substantially as described. 25
24. In combination, a table, means for pushing can bodies onto said table from the edge thereof inwardly, a series of arms traveling with their ends substantially along the plane of the table's edge, said arms being spaced apart to receive the can bodies between them and being mounted to yield on striking a can body end on, and means accelerating the speed of the fingers between 30 the point of taking the can bodies and the point of discharge to respace the can bodies, substantially as described. 35

In testimony whereof we affix our signatures.
